TICKET APPLYING MACHINE

Elmer C. Hake, Covington, Ky., assignor, by mesne assignments, to Spray-Omatic Products Company, Cincinnati, Ohio, a corporation of Ohio

Application February 1, 1943, Serial No. 474,376

10 Claims. (Cl. 93—88)

1 This invention relates to a ticket applying machine, that is, a machine adapted to accomplish the application of tickets successively to papers or sheets introduced into the machine. The device of the invention is designed to operate in conjunction with a special form of ticket, herein disclosed, which may be a price tag or some other type of identifying ticket to be detachably applied to the margins of cards, sheets, or similar objects. By way of example, Fig. 10 illustrates a ticket in the form of a price tag applied over the edges of two flat sheets held together by said ticket, which sheets might conceivably be a card and an envelope therefor, or perhaps a plurality of cards. A single sheet or card, of course, might be similarly marked or identified by the tag or ticket.

An object of the invention is to expedite and facilitate the application of tickets or tags to sheet-like articles as a rapid continuous operation.

Another object of the invention is to produce a machine of the character stated, which is simple, inexpensive, and dependable in the performance of its operations, so that long periods of trouble-free service are assured with a minimum of expense and servicing.

Another object is to reduce to a minimum the number of moving parts in a machine of the character disclosed, for the attainment of various obvious advantages including ease of operation and simplicity in the charging of the machine with tickets when the supply is exhausted.

The foregoing and other objects are attained by the means described herein and disclosed in the accompanying drawings, in which:

Fig. 1 is a side elevational view of the ticket applying machine, part of the ticket reel being broken away.

Fig. 2 is an enlarged cross-sectional view taken on line 2—2 of Fig. 3.

Fig. 3 is a fragmental plan view of the machine shown in Fig. 1, parts being broken away in the interest of clarity of disclosure.

Fig. 4 is a perspective view of a guard.

Fig. 5 is a perspective view of a presser element.

Fig. 6 is a perspective view of a ticket feed guide.

Fig. 7 is a perspective view of a cut-off member.

Fig. 8 is a side view of a strip of tickets of the type accommodated by the machine of the invention.

2 Fig. 9 is a view looking down on Fig. 8, showing the ticket strip in plan.

Fig. 10 is a fragmental plan view of two sheets or cards, with a ticket attached thereto by means of the machine herein disclosed.

Fig. 11 is a cross-sectional view similar to Fig. 2, but with the guard omitted, showing the manner in which tickets are fed in the machine.

The ticket applying machine and its operation may be best understood following a description of the tickets themselves, which are of special form as illustrated by Figs. 8, 9, 10 and 11 of the drawings. A complete ticket comprises a strip of paper folded upon itself along a line 13, to provide a short leg 14 and a long leg 15 disposed in substantial parallelism, the legs of the ticket being yieldingly urged toward each other by means of a U-shaped clip 16 that straddles the fold line 13 of the ticket. Clip 16 may be of metal, plastic, cellulosic composition material, or the like, and the character thereof should be such that it will normally remain associated with the legs of the ticket, and be sufficiently yieldable to enable the insertion of a card, a sheet, or a limited number of cards or sheets to be inserted between the legs of the ticket to the extent indicated by Fig. 10. It will be noted that the characters 17 and 18 represent two sheets or cards, or perhaps a card and an envelope, which are held together along a common edge margin by means of the ticket above described. The common upper edges of the cards or sheets will be seen to extend to the line of fold 13 of the ticket. The clip 16 serves to firmly hold the sheets or cards between the ticket legs, although it is to be understood that the ticket may be detached by simply sliding it upwardly off the margins of the cards or sheets. By means of suitable indentations 19 or other frictional expediency, a reasonably secure mounting of the clip relative to the ticket is assured. One of the legs such as 14 may carry suitable indicia, such as a price marking or other identifying character intended to apply to the sheets or cards upon which the ticket is mounted. Preferably, though not of necessity, the corners of the ticket at the opposite ends of the fold line 13, may be cut off or otherwise removed as at 20.

In the operation of the ticket applying machine, tickets such as 14—15 arranged in continuous strip form, as illustrated by Figs. 8 and 9, are successively fed to a station at which an operator manually advances the cards or sheets between the ticket legs until the Fig. 10 relationship is attained, and thereafter a slight ad-

ditional advancement of the cards or sheets effects a severance of the applied ticket from the next adjacent ticket of a group such as Fig. 8 illustrates. Upon completion of the severing operation, the operator merely retracts the cards or sheets with the ticket attached (Fig. 10), thereby completing the operation. It will be understood that the attachment of price tickets or tags to greeting cards and envelopes therefor, by way of example, may be expeditiously accomplished by the use of the present machine in the hands of a steady operator.

As a final remark touching the character of the ticket assembly, it may be noted that the meeting edges, or line of severance 21 between adjacent tickets, preferably is a weakened or partially perforated area, as is best illustrated by Fig. 9. The transverse cuts or slots 21 leave relatively weak connective sections 22 between adjacent tickets. These connective sections are easily severed by the knife or cutter of the machine (Fig. 7).

The ticket applying machine as illustrated by Figs. 1 and 3, comprises a hollow casing 23 having a top 24 upon which is mounted the ticket guide and cutter mechanism. At the front of the machine a handle 25 may be provided for operating the ticket feed and cutter mechanism. The lever arm 26 and certain linkage associated therewith may be contained within a sheet metal cover 27 which meets the casing 23 along an irregular line 28, and may be attached to said casing by means of screws or the like 29. These casing and cover details are of no particular importance to the invention, but are referred to merely because the present form of machine incorporates them. In fact, it is necessary only that some means be provided for pivotally mounting the operating lever, as at 30, and that suitable support be provided for a stationary table 31 and the ticket feeding and cutting means located at the right of the table.

Referring to page 2 of the drawings, the characters 32, 33, 34 and 35 illustrate, respectively, a guard, a spring, a ticket guide member, and a blade or knife. As may best be seen from Fig. 2, the top of the casing carries a longitudinal slot 36 through which depends a forwardly and rearwardly traveling post 37 which is adapted to be moved through the agency of linkage 50 associated with the handle lever 26. The linkage may be of any suitable design, that shown in Fig. 1 consisting of a bell crank 38 pivoted upon the casing of the machine at 39, and having its forward end pivoted at 40 upon a short link 41 that is loosely pinned at 42 upon the handle lever. The upstanding arm 43 of the bell crank may be pivotally attached to a link 44 loosely pinned to the post 37. The post at 45 is securely attached to a reciprocable knife or blade holder 46 which is adapted to slide lengthwise over the slot 36 of the casing.

By referring to Fig. 1, it will be understood that an elevating movement of handle 26 to its upper limit of travel, indicated at 47, which is 65 the upper end of a slot formed in the cover 27, will move the bell crank 38-43 in clockwise direction about its pivot 39, to shift the post 37 and its associated blade holder 46 to the right, so that the blade 35 will be retracted away from the feed table 31. A suitable top plate 48 secured to the top of the casing furnishes a channel 49 in which the cutter or knife assembly may reciprocate. Any suitable type of connection may be made between the blade holder 46 and the

blade 35, the connection shown herein being simply a transverse slot 50 in the holder 46 adapted to receive the turned end 51 of the blade or cutter. The flat spring 33 overlies the blade or cutter for the purpose of pressing against the latter the succession of tickets, as indicated by Fig. 11. The spring serves to flatten the ticket strip so as to condition the tickets for reception of cards or sheets indicated by the characters 17 and 18 of Fig. 11. It will be noted that the tickets are not so flattened as they advance along the ticket guide 34 before reaching the spring 33. This is plainly indicated by Fig. 1, wherein a series of tickets is shown leaving a reel or spool 52.

The guard 32 (Fig. 4) may consist of a stamping having at one end a pair of perforated ears 53-53 for mounting of the guard upon the top of an inverted U-shaped standard 54, said guard having depending opposed aprons 55 adapted to rest upon the opposed anchorage plates 56-56 of the ticket guide member 34, under normal operating conditions. Forwardly of the aprons, the guard has a pair of spaced parallel side portions 57-57, the lower edges 58 of which serve as tracks to guide the sheets or cards between the legs of the tickets when the sheets or cards are advanced along the stationary feed table 31. The track edges 58 depend slightly beneath the level of the blade 35, as illustrated by Figs. 1 and 2, and while the guard is omitted from Fig. 11, it will readily be understood that the track edges of the guard will guide the advancing edges of cards or sheets 17 and 18 beneath the blade and between the legs of the foremost ticket. Thus, no ticket other than the foremost one may be contacted by the cards or sheets fed toward the blade by an operator stationed at the front of the machine, and manipulating cards or sheets flatwise along the feed table 31 in the direction of the cutter. As the operator so feeds the cards or sheets, the advance edges thereof will enter between the legs of the foremost ticket A until the limit of advancement is attained, 45 whereupon further force exerted by the operator will cause the cutter to sever the foremost ticket from the next adjacent ticket. The cards or sheets with the ticket attached, may then be retracted along the feed table by the operator.

Upon withdrawing the sheet and ticket assembly in the condition illustrated by Fig. 10, it will be evident from Fig. 11 that the foremost ticket there illustrated will be removed from its position beneath the blade or cutter 35. To bring another ticket into receptive position, the operator will elevate the handle 25, thereby to move the cutter assembly of Fig. 11 to the right a distance sufficient to allow the next ticket B to drop, so that its associated clip will fall beneath the level of the blade 35 while the longer leg 15 of the ticket rests upon the depressed portion 59 of the feed plate. Subsequent lowering of the handle obviously will advance the cutter or blade 35 to the left, over the clip of ticket B, and this ticket will thereupon be advanced to take the place of the foremost ticket previously dispensed. The mechanism is then ready for a subsequent feeding of cards or sheets along the table 31 to repeat the ticket applying operation. It will accordingly be understood that each ticket applying operation must be preceded by an elevating and lowering movement of the handle 25. The handle may be weighted or otherwise arranged to normally assume the lowered position

indicated by Fig. 1, at which position the blade or cutter is fully advanced, (Fig. 11).

It may here be noted that the ticket guide incorporates an abutment at the location 60, and against which may impinge the clip of a third ticket C whenever the blade is retracted, the purpose of this being to preclude retrograde movement of the ticket strip when the blade is so retracted. A second abutment 74 may be provided, if desired, to limit the advance of the card or sheet, and to finally seat the ticket fully upon the card or sheet margins.

Tickets in the accordian pleated form illustrated by Fig. 8 may be fed along the ticket guide 34 from any suitable source of supply. As herein illustrated, the ticket strip is wound upon a reel which may be supported upon a shaft 61 journaled in a bracket 62 which may be fastened to the rear of the casing by means of a screw 63 or other fastening means. Each reel may consist of a disc 52 and a hub 64 fastened together as a unit, and several such units may be mounted for free rotation upon shaft 61. Fig. 3 shows a series of five reel units, any one of which may be shifted into alignment with the ticket guide 34 for supplying tickets to the machine. Any selected reel may be aligned with the ticket guide by shifting the reels lengthwise of shaft 61, the purpose of so doing being to enable the selective feeding of the tickets bearing different price or identification markings. For example, the first reel may carry 5¢ tickets, the second may carry 10¢ tickets, the third may carry 15¢ tickets, etc. The length of shaft 61 should be so calculated that either endmost reel may be aligned with the ticket guide 34. It should be appreciated that the tickets in accordian pleated form will be wound upon a reel in the same manner as would a strip of flat tickets. The reel will rotate, therefore, as the tickets are dispensed by the machine.

The mounting of the guard 32 and spring 33 upon the upper end of the standard 54—54 may be accomplished in any suitable manner by means of a pin passing through the upper perforated ends 65 of the standard. Such pin may pass through the eye 66 of the spring and through the perforated ears 53 of the guard. To avoid the need for a separate element to hold the guard down against the mounting flanges 56 of the ticket guide, the pivot for the guard may be made in the form of a U-shaped spring member 67 having inwardly turned free ends 68—68 adapted to engage in opposed perforation 69 of the aprons 55 of the guard. These inturned ends 68 also pass through corresponding perforations 70 formed in the sides of the ticket guide so that the guard will be locked to the stationary guide through the agency of the inturned ends 68 of the spring member 67. The transverse connecting portion 71 of the spring member furnishes the pivotal mounting for both the guard and the flat spring 33. The pivotal mounting for the guard and spring is furnished in order that these parts may be lifted and moved to inoperative position when it becomes necessary or desirable to charge the machine with a new or different strip of tickets. The character 72 indicates a finger piece at the free forward end of the guard, which may be grasped in lifting the guard and rotating it about its pivot 71 for gaining access to the forward end of the ticket guide. As will be understood, the guard, in order to be so moved to the inoperative position, must be released by

withdrawing the turned ends 68 of the spring wire 67 from the apertures 69 of the guard.

The parts illustrated by Figs. 4, 5, 6 and 7 are shown in the relative positions they occupy when assembled, that is, the knife 35 is operative beneath the ticket guide member of Fig. 6, and the spring of Fig. 5, pivoted at 65, overlies the forward end of the guide member. Guard 32 (Fig. 4), covers the spring and is pivoted likewise at 65. As previously stated herein, the guard normally is precluded from pivoting, by aligning the opening 69 thereof with the opening 70 of the guide member, and inserting through the openings the inturned ends of the anchor element 67. This sub-assembly, of course, is capable of considerable modification by resorting to mechanical equivalents. Moreover, other changes in details of the device at once suggest themselves, for example, the use of spring means instead of a weighted handle for returning the handle lever 26 to normal position, or the substitution of different linkage and operating means therefor. Disposition of the operating lever to one side of the machine housing, rather than at the front thereof, also may be considered a change falling within the scope of the invention.

From all of the foregoing, it should be evident that the ticket applying machine herein disclosed is extremely simple in construction and operation, and that few moving parts are necessary. The machine is portable, and may easily be carried with one hand, for use wherever it may be needed. The ticket guide member 34 serves as a carrying handle. In practice, the machine herein disclosed has been used for applying price tickets to greeting cards and envelopes therefor, but as will be obvious, the application of clip-type tickets to sheets or cards for various other purposes is well within the range of use of the machine.

What is claimed is:

1. In a machine for applying connected accordian folded tickets each of which includes a fold line and a pair of legs extending in a common direction from the fold line, the combination which comprises, means for supporting the foremost ticket of a group with the legs of said folded ticket projected toward the front of the machine, said legs being receptive of a flat object to be advanced therebetween to the fold line of the ticket, cutting means normally held stationary between the foremost ticket and a subsequent ticket of the group as the flat object is so advanced, to sever the connection between the foremost ticket and the next adjacent ticket upon continued advancement of the flat object in the direction of the ticket fold line, and means for momentarily retracting the cutting means after removal of the flat object and the severed ticket, to permit replacement of said ticket by a subsequent ticket of the group.

2. In a machine for applying connected accordian folded tickets each of which includes a fold line and a pair of legs extending in a common direction from the fold line, the combination which comprises, means for supporting the foremost ticket of a group with the legs of said folded ticket projected toward the front of the machine, said legs being receptive of a flat object to be advanced therebetween to the fold line of the ticket, reciprocable means normally held stationary between the foremost ticket and a subsequent ticket of the group as the flat object is so advanced, to sever the connection between the foremost ticket and the next adjacent ticket upon

continued advancement of the flat object in the direction of the ticket fold line, and means for reciprocating said normally stationary securing means, to advance the next adjacent ticket into position for reception of a subsequent flat object between the legs thereof.

3. In a machine for applying connected accordian folded tickets each of which includes a fold line and a pair of legs extending in a common direction from the fold line, the combination which comprises, means for supporting the foremost ticket of a group with the legs of said folded ticket projected toward the front of the machine, said legs being receptive of a flat object to be advanced therebetween to the fold line of the ticket, reciprocable means normally held stationary as the flat object is so advanced, to sever the connection between the foremost ticket and the next adjacent ticket upon continued advancement of the flat object in the direction of the ticket fold line, means for reciprocating said normally stationary severing means, to advance the next adjacent ticket into position for reception of a subsequent flat object between the legs thereof, and means precluding retrograde movement of the group of tickets during reciprocation of said normally stationary means.

4. In a machine of the class described, the combination of a substantially flat severing member normally extended, and means pressing onto one face of said severing member a folded ticket of a group of connected tickets each of which includes a fold line and a pair of legs extending in a common direction from the fold line, a stationary support beneath the plane of the severing member to underlie a sheet to be advanced toward the severing member, means for retracting the severing member from a normal position between the foremost ticket and a subsequent ticket of the group, to displace the face thereof from supporting relationship with said foremost ticket, whereby said ticket drops to proximity with the stationary support in position to receive the sheet between the legs thereof, and abutment means adjacent to the severing member for engaging the fold edge of an adjacent ticket to preclude retrograde movement of the ticket as the severing member is retracted, the severing member when returned to the normally extended position passing over the dropped ticket and into supporting relationship with the next adjacent ticket.

5. In a machine of the class described, the combination of a substantially flat severing member normally extended, and means pressing onto one face of said severing member a folded ticket of a group of connected tickets each of which includes a fold line and a pair of legs extending in a common direction from the fold line, a stationary support beneath the plane of the severing member to underlie a sheet to be advanced toward the severing member, and means for retracting the severing member to displace the face thereof from a normal supporting relationship with said folded ticket, whereby said ticket drops to proximity with the stationary support in position to receive the sheet between the legs thereof.

6. In a machine of the class described, the combination of a substantially flat severing member normally extended, and means pressing onto one face of said severing member a folded ticket of a group of connected tickets each of which includes a fold line and a pair of legs extending in a common direction from the fold line, a sta-

tionary support beneath the plane of the severing member to underlie a sheet to be advanced toward the severing member, means for retracting the severing member to displace the face thereof from a normal supporting relationship with said folded ticket, whereby said ticket drops to proximity with the stationary support in position to receive the sheet between the legs thereof, the severing member when returned to the normally extended position passing over the dropped ticket and into supporting relationship with the next adjacent ticket.

7. In a machine of the class described, the combination of a substantially flat severing member normally extended, and means normally pressing onto one face of said severing member a folded ticket of a group of connected tickets each of which includes a fold line and a pair of legs of unequal length extending in a common direction from the fold line to accept a sheet advanced therebetween, a support beneath the severing member and spaced therefrom to provide a surface upon which the longer leg of the ticket may rest while the shorter leg and the fold underlie the severing member in position to accept said sheet, and while the longer leg of a next adjacent ticket rests normally over and upon the severing member, and means for momentarily retracting the severing member from supportive relationship with said last mentioned longer leg of said next adjacent ticket, after removal of the ticket first mentioned, to position the legs of said next adjacent ticket for reception of another sheet to be advanced therebetween as above stated.

8. In a machine of the class described, the combination of a substantially flat severing member normally extended, and means normally pressing onto one face of said severing member a folded ticket of a group of connected tickets each of which includes a fold line and a pair of legs of unequal length extending in a common direction from the fold line to accept a sheet advanced therebetween, a support beneath the severing member and spaced therefrom to provide a surface upon which the longer leg of the ticket may rest while the shorter leg and the fold underlie the severing member in position to accept said sheet, and while the longer leg of a next adjacent ticket rests normally over and upon the severing member, means operative after removal of the ticket first mentioned, for momentarily retracting the severing member from supportive relationship with the last mentioned longer leg of said next adjacent ticket, and means substantially precluding retrograde movement of said next adjacent ticket incident to retraction of the severing member, while allowing the longer leg of said next adjacent ticket to drop onto the support to replace the ticket previously removed.

9. In combination in a machine for applying connected accordian folded tickets each of which includes a fold line and a pair of legs extending in a common direction from the fold line, said legs being receptive of a flat object to be advanced therebetween to the fold line of the ticket, cutting means normally held stationary between the foremost ticket and a subsequent ticket of a group as the flat object is so advanced, to sever the connection between the foremost ticket and the next adjacent ticket upon continued advancement of the flat object in the direction of the ticket fold line, and means for normally retracting the cutting means after removal of the flat object and the severed ticket, to permit replacement of said ticket by a subsequent ticket of the group.

10. In a machine of the class described, the combination of a substantially flat severing member normally extended, and means normally pressing onto one face of said severing member a folded ticket of a group of connected tickets each of which includes a fold line and a pair of legs of unequal length extending in a common direction from the fold line to accept a sheet advanced therebetween, the shorter leg of the foremost ticket underlying the severing member while the longer leg of a subsequent ticket overlies the severing member, means operative after removal of the foremost ticket for normally retracting the severing member from supportive relationship with the longer leg of said next adjacent ticket, and means substantially precluding retrograde movement of said next adjacent ticket incident

to retraction of the severing member, while allowing the longer leg of said next adjacent ticket to drop to a level beneath the plane of the severing member.
